UNITED STATES PATENT OFFICE

105,722

DESIGN FOR A MASSAGE IMPLEMENT

Edward T. Widmann, Washington, D. C.

Application December 23, 1936, Serial No. 66,715

Term of patent 14 years

To all whom it may concern:

Be it known that I, Edward T. Widmann, a citizen of the United States, residing at Washington, in the District of Columbia, have invented a new, original, and ornamental Design for Massage Implements, of which the following is a specification, reference being had to the accompanying drawing, forming part thereof, and of which Fig. 1 represents a front view, Fig. 2 a side view, Fig.

3 a back view, and Fig. 4 a top view of a massage implement showing my new design.

The characteristic feature of my design resides in the head portion.

I claim:—

The ornamental design for a massage implement, as shown and described.

EDWARD T. WIDMANN.
